TREATMENT OF SOUR PETROLEUM
DISTILLATES

Albert J. Shmidl, Houston, Tex., assignor, by
mesne assignments, to Standard Oil Develop-
ment Company, Elizabeth, N. J., a corporation
of Delaware

No Drawing. Application February 19, 1949,
Serial No. 77,443

9 Claims. (Cl. 196—29)

1

The present invention is directed to a method for treating sour petroleum distillates. More particularly, the invention is directed to the sweetening of sour petroleum distillates in the presence of an alkali metal hydroxide and a mild oxidizing agent.

Prior to the present invention, it has been known to treat sour petroleum distillates with aqueous alkaline solutions, such as solutions of alkali metal hydroxide, to remove hydrogen sulfide and other acidic bodies, following which the sour distillates were treated with sodium plumbite solution to convert deleterious sulfur compounds to compounds which are largely innocuous. This and other prior art processes relied on the addition of sulfur to cause the conversion of the sulfur compounds from mercaptans to disulfides. Other processes convert the undesirable compounds by means of lead sulfide which is then separated from the gasoline. Frequently, the separation of lead sulfide from the gasoline was not complete, and consequently, some was carried over into storage, which was disadvantageous. Furthermore, the addition of sulfur to gasoline frequently impaired the octane number level of the gasoline since it is well known that sulfur and its compounds affect gasoline detrimentally.

Efforts have been made in the prior art to remedy this situation, and the workers in the field have turned to adding certain compounds, such as phenols and amines, to alkaline solutions, such as sodium hydroxide, to cause conversion through an oxidation mechanism of the deleterious compounds in the sour naphtha. Frequently such expedients are unsatisfactory in not completely sweetening the product, and an after-treatment, by one of the well known procedures, becomes necessary.

From the foregoing discussion of the prior art, it will be seen that the petroleum refining industry has been faced with a problem of converting deleterious sulfur compounds present in petroleum distillates to those which do not detrimentally affect the quality of the product.

It is, therefore, the main object of the present invention to provide a treating process in which improved results are obtained in converting objectionable sulfur compounds to harmless bodies.

Another object of the present invention is to provide an improved sweetening process in which an active material is added to the petroleum distillate being sweetened to catalyze the conversion of deleterious sulfur compounds.

Another object of the present invention is to provide an improved sweetening process in which

2

small amounts of catalytic reagents are employed.

In the foregoing description of the prior art, it will be seen that the prior art workers added compounds such as phenols and certain amines to the alkaline solutions which were employed to treat sour petroleum distillates. I have now found that, in distinction to the prior art workers, improved results may be obtained by adding catalytic amounts of an alcoholic amine to the sour petroleum distillate. Therefore, in accordance with the present invention the foregoing objects may be achieved by adding to sour petroleum distillates small amounts of alkanol amines and then contacting the sour distillates containing the alkanol amine with a very small catalytic quantity of a solution of an alkali metal hydroxide while maintaining in contact therewith a mild oxidizing agent.

Accordingly, it may be seen that the present invention may be described briefly as involving treating a sour petroleum distillate boiling in the range from about 50° to 750° F. by contacting the distillate with a solution of an alkali metal hydroxide while maintaining in the sour distillate a catalytic amount of an alkanol amine and adding to the contacted mixture a mild oxidizing agent sufficient to sweeten said distillate, following which the alkali metal hydroxide is separated from the contacted distillate.

The alkanol amines employed in the practice of the present invention include the ethanol amines such as mono-, di-, and triethanol amine, the mono-, di-, and tripropanol and butanol amines and the higher members of the same homologous series. The compounds used in the present invention have the general structural formula $\text{NH}_3-x(\text{C}_y\text{H}_{2y}\text{OH})_x$ where N is the amine nitrogen, x is an integer from 1 to 3, and y is an integer from 1 to 18, inclusive.

These compounds may be employed in amounts, based on the naphtha, varying from 0.001 to 1.0 per cent by volume, with a preferred range from about 0.01 to 0.15 per cent by volume. It is to be emphasized that the specified amount of the alkanol amines should be added to the naphtha and not to the alkaline solution. These compounds are employed generally in a small amount effective to sweeten the naphtha in accordance with the present invention and may exert a catalytic action on the sweetening operation.

The alkaline solution employed in the present invention should be a solution of an alkali metal hydroxide. Preferably the solution should be an aqueous solution having a Baumé gravity

in the range from about 30° to 50° Bé. but solutions of lower strengths may be used under some conditions. For example, a 40° Bé. aqueous solution of sodium hydroxide gives satisfactory results.

The alkali metal hydroxide may be lithium, sodium, or potassium hydroxide, but sodium hydroxide will be preferred on account of its availability.

The temperature at which the treating operation is conducted will usually be atmospheric temperature and may range from about 60° F. up to about 120° F., although higher temperatures up to 200° F. may be used. A preferred temperature range will be from about 70° to about 95° F. Satisfactory results have been obtained at atmospheric temperatures encountered in the Texas Gulf Coast area.

The present invention will be further illustrated by the following specific example:

EXAMPLE I

A portion of a hydrogen sulfide free refined kerosene, which was a solvent raffinate having a copper number of 50 and a Saybolt color of 20, was divided into two parts. To one part was added 0.05% by volume of triethanol amine and the stock was then contacted with 5% by volume of 40° Bé. sodium hydroxide solution in the presence of three times the theoretical amount of oxygen required to sweeten, employing two minutes' agitation in an agitator equipped with paddles operating at 1200 revolutions per minute. The second portion was contacted with 5% by volume, based on the kerosene, of 15° Bé. sodium hydroxide solution to which had been added 0.05% by volume, based on the kerosene, of triethanol amine. The kerosene was then contacted with the sodium hydroxide solution of triethanol amine in the presence of three times the theoretical amount of oxygen for two minutes under violent agitation in an agitator equipped with paddles, operating at 1200 revolutions per minute. The sodium hydroxide solution was separated from each of the two treated portions of the kerosene and the copper number and color of the treated kerosenes determined. The data in the first column of Table I represent the treatment in accordance with the present invention whereas the data in column 2 represent prior art techniques where the catalyst is added to the sodium hydroxide rather than to the kerosene.

Table I

	1	2
Copper No.:		
Immediately.....	32	52
After 1 Hour.....	25	50
After 3 Hours.....	23	50
After 24 Hours.....	8	50
Saybolt Color.....	20	-12

The data in Table I indicate the markedly superior result obtained by treatment of the kerosene in accordance with the present invention, in which the triethanol amine was added prior to contact with sodium hydroxide in the presence of oxygen over that obtained when treating in accordance with the prior art methods in which the kerosene was contacted with a sodium hydroxide solution of triethanol amine. The copper number of the naphtha treated according to my invention was reduced to 32 after contact with sodium hydroxide, and dropped to 25 after 1 hour, to 23 after 3 hours, and to 8 after

24 hours, whereas that of the kerosene treated conventionally was substantially unchanged. Of great significance is the color of the kerosene to which triethanol amine had been added and which was treated in accordance with the present invention. It will be noted that the color after 24 hours was 20, the same as the kerosene initially, whereas the color of the kerosene when treated in accordance with conventional techniques had dropped to -12. The color of the kerosene treated in accordance with the present invention was even better than that of kerosene treated only with 40° Bé. sodium hydroxide, since the latter dropped to 18 after standing in storage for 24 hours.

In the foregoing example, the improvement obtained in the present invention has been illustrated by the copper number test. This is a well known analytical procedure employed in the petroleum industry. A description of the method of test may be found in "U. O. P. Laboratory Test Methods for Petroleum and Its Products," third edition, page H-61, Universal Oil Products Company, Chicago, 1947. This test is a measure of the mercaptan sulfur content of the oil being tested.

(In the practice of the present invention, it is to be understood that the sour petroleum distillates employed as feed stocks are free from, or deficient in catalytic, oxidation promoting compounds and will not sweeten in contact with a mild oxidizing agent and alkali metal hydroxide. The great majority of petroleum distillates to be sweetened in general refinery practice will be found to fall in this category.

Although not illustrated by the example, one of the particular advantages of the present invention resides in the catalytic effect of the alkali metal hydroxide solution. The alkali metal hydroxide appears to function as a true catalyst since the small amount used may be recycled to treat large quantities of sour petroleum distillate. A small amount of the alkali metal hydroxide solution may be entrained in the treated naphtha, and, therefore, it may be necessary to replace the entrained amount with fresh solution. In short, it is contemplated in the practice of the present invention that the alkali metal hydroxide solution will be reused over and over again, since it is not necessary to regenerate this solution.

The invention has been described and illustrated by employment of a mild oxidizing agent such as oxygen. It is contemplated that mixtures of oxygen with other gases, such as air, may be employed. It is also contemplated that other mild oxidizing agents such as peroxides, permanganates, and the like may be used. For example, a hydrogen peroxide solution may be employed as the mild oxidizing agent.

In practicing the present invention, it is to be understood that the petroleum distillate may be subjected to a preliminary treatment for removal of hydrogen sulfide if the distillate contains hydrogen sulfide. Such preliminary treatment may include washing with a dilute alkali metal hydroxide solution or blowing with a free-oxygen containing gas such as air. If hydrogen sulfide and/or other acidic compounds are present and are not removed, the alkali metal hydroxide solution employed as the catalyst may very quickly become seriously depleted in activity.

In the practice of the invention, it will be desirable to use an amount of oxygen in excess of the theoretical required to sweeten the sour petroleum distillate. Ordinarily, an amount of about

300% of the theoretical amount to sweeten may be employed. However, sweetening in accordance with the present invention may be obtained with considerably lesser quantities of oxygen. In fact, sweetening may be obtained in some cases by contact with the oxygen present in the treating vessel. It will be desirable to employ an amount of oxidizing agent at least equivalent to the theoretical amount required to sweeten.

The invention has been described and exemplified by employment of 0.5 to 5.0% by volume of the catalytic alkali metal hydroxide solution. It is contemplated that as little as 0.1 and as much as 5% by volume, or more, of the alkali metal hydroxide solution, based on the sour naphtha, may be employed. Very good results, however, are obtained with 1% by volume and this amount will be preferred.

The nature and objects of the present invention having been completely described and illustrated, what I wish to claim as new and useful and to secure by Letters Patent is:

1. A method for sweetening a sour petroleum distillate containing mercaptans and having a final boiling point no greater than 750° F. which comprises adding to said distillate a small but effective catalytic amount no greater than 1% by volume of an alkanol amine and, then agitating the distillate containing the alkanol amine with a small amount no more than 5% by volume of a solution of an alkali metal hydroxide while adding a sufficient amount of a mild oxidizing agent to convert the mercaptans to disulfides and to obtain a sweetened distillate.

2. A method in accordance with claim 1 in which the alkanol amine is an ethanol amine.

3. A method in accordance with claim 1 in which the alkanol amine is a propanol amine.

4. A method in accordance with claim 1 in which the alkanol amine is a butanol amine.

5. A method in accordance with claim 1 in which the alkanol amine is employed in an amount in the range from 0.001 to 1.0% by volume of the sour petroleum distillate.

6. A method in accordance with claim 1 in which the mild oxidizing agent is a free-oxygen containing gas.

7. A method for sweetening a sour petroleum distillate containing mercaptans and having a

final boiling point no greater than 750° F. which comprises adding to said distillate a small but effective catalytic amount no greater than 1% by volume of triethanol amine and then agitating the distillate containing triethanol amine with no more than 5% by volume of an aqueous solution of an alkali metal hydroxide while adding a sufficient amount of mild oxidizing agent to convert the mercaptans to disulfides and to obtain a sweetened distillate.

8. A method for sweetening a sour petroleum distillate containing mercaptans and having a final boiling point no greater than 750° F. which comprises adding to said distillate an amount of triethanol amine in the range between 0.001% and 1.0% based on said distillate and then agitating the distillate containing triethanol amine with an effective amount of a sodium hydroxide solution not over 5% by volume based on the sour distillate while adding a sufficient amount of a free oxygen containing gas to convert the mercaptans to disulfides and to obtain a sweetened distillate.

9. A method for sweetening a sour petroleum distillate containing mercaptans and having a final boiling point no greater than 750° F. which comprises adding to said distillate 0.05% by volume of triethanol amine based on the distillate and then agitating the distillate containing triethanol amine with 5% by volume based on the sour distillate of an aqueous 40° Bé. sodium hydroxide solution while adding three times the theoretical amount of oxygen required to convert the mercaptans to disulfides and to obtain a sweetened distillate.

ALBERT J. SHMIDL.
